UNITED STATES PATENT OFFICE

166,952

WORLD CLOCK

Warren H. Clarke, New York, N. Y., assignor to
Kalex Corporation, New York, N. Y., a corpora-
tion of New York

Application September 28, 1951, Serial No. 16,771

Term of patent 14 years

(Cl. D42—7)

To all whom it may concern:

Be it known that I, Warren H. Clarke, a citizen of the United States, residing in New York city, in the county of New York and State of New York, have invented a new, original, and ornamental Design for a World Clock, of which the following is a specification, reference being had to the accompanying drawings, forming a part hereof.

Fig. 1 is a front perspective view of a world clock, showing my new design;

Fig. 2 is a side elevational view of the same; and

Fig. 3 is a bottom perspective view thereof.

I claim:

The ornamental design for a world clock, as shown.

WARREN H. CLARKE.
